POVL HARTMANN, OF BROOKLYN, NEW YORK, ASSIGNOR TO CHARLES L. EIDLITZ CO.,
OF NEW YORK, N. Y., A CORPORATION OF NEW YORK.

DESIGN FOR AN ELECTRICAL RECEPTACLE FOR CEILING-BOXES.

59,216.

Specification for Design.

Patented Oct. 4, 1921.

Application filed May 4, 1921. Serial No. 466,700. Term of patent 14 years.

To all whom it may concern:

Be it known that I, POVL HARTMANN, a subject of the King of Great Britain, and resident of the borough of Brooklyn, county of Kings, city and State of New York, have invented a new, original, and ornamental Design for Electrical Receptacles for Ceiling-Boxes, of which the following is a specification.

In the accompanying drawings, Figure 1 is a plan view of an electrical receptacle

showing my new design; Fig. 2 is a front elevation thereof and Fig. 3 is an end elevation thereof.

The essence of my invention resides in the design of the electrical receptacle as a whole, substantially as shown and described.

I claim:

The ornamental design for an electrical receptacle for ceiling boxes, as shown and described.

POVL HARTMANN.
